UNITED STATES PATENT OFFICE.

WILLIAM C. BROWNING AND THOMAS M. LOWE, OF MANBAR, WEST VIRGINIA.

RAIL-JOINT.

1,237,612.

Specification of Letters Patent. Patented Aug. 21, 1917.

Application filed June 8, 1917. Serial No. 173,553.

To all whom it may concern:

Be it known that we, WILLIAM C. BROWNING and THOMAS M. LOWE, citizens of the United States, and residents of Manbar, in 5 the county of Logan and State of West Virginia, have invented certain new and useful Improvements in Rail-Joints, of which the following is a specification.

The present invention relates to an improved rail joint, and it is the primary object of the invention to provide a rail joint, which, when engaged with the web portions of the abutting rail sections, will positively prevent undue transverse or longitudinal 15 movement thereof.

It is also an object of the invention to provide a rail joint having hingedly mounted angle plates, whereby the same may be swung into clamping engagement 20 with the rail sections.

Another object of the invention is to provide a novel base plate for the joint, the same being so constructed as to permit the hinged mounting of the angle plates thereon 25 and to prevent creeping thereof with relation to the ties.

Among other aims and objects of the invention may be recited, the provision of a joint of the character mentioned with a 30 view to compactness, and in which the parts are few, the construction simple, the cost of production small and efficiency and operation high.

The improvements in the details and arrangement of parts will be apparent from an inspection of the accompanying drawings, in connection with the specific description hereinafter contained, and wherein the preferred embodiment of the 40 invention is disclosed for the purpose of imparting a full understanding of the same.

In the drawings:

Figure 1 is a top plan of our improved 45 joint, the rail being shown in horizontal section;

Fig. 2 is a side elevation of the same;

Fig. 3 is an end elevation; and

Fig. 4 is a perspective of the base plate.

50 Referring now more particularly to the several figures of the said drawings and in connection with which like reference numerals will refer to corresponding parts, there is provided, a base plate designated 1, 55 the opposite ends of which are bent downwardly to provide a pair of oppositely dis-

posed depending lips 2 adapted for engagement with the opposite extremities of the usual cross ties 2. Pairs of oppositely disposed apertured beveled lugs 4 are formed 60 integral with the upper face of the base plate 1, at points adjacent the depending lip portions 2 thereof and are adapted to receive therebetween the base portions of the abutting rail sections 5 and 5'. A plurality of openings 6 are formed within the base plate 1 and obviously, permit the introduction of spikes 7 therethrough into engagement with the ties 3, whereby, the said plates may be secured in position. 70

A plurality of angle plates 8 having apertured laterally extending lugs 9 formed upon the opposite extremities thereof longitudinally of the base plate 1, the said laterally extending lugs 9 engaging the opposite 75 faces of the various lugs 4, whereupon, pivot bolts or other connections 10 are passed through the alined openings. By so connecting the angle plates with the base plate of the joint, swinging of the same into 80 clamping and idle positions will be facilitated, thereby rendering the placing of the abutting ends of the rail sections therebetween a comparatively easy operation. A series of openings are formed within the 85 upper portions of the angle plates and are adapted to be alined with similarly arranged openings formed in the web portions of the abutting web sections, whereby connecting bolts 11 may be passed therethrough 90 and locking nuts 12 turned into engagement with the same.

With our improved rail joint, transverse or longitudinal creeping of the rail sections is prevented, since, the base plate 1 by reason of the engagement of the spikes will brace the same against transverse movement, while the connection between the angle plates and the web portions of the rail sections will brace the same against 95 longitudinal movement. The plates may be readily disengaged from the web portions of the rail sections, by removing the bolts 11 and the locking nuts 12 and then swinging the said plates backwardly upon their 100 respective pivots. It is to be understood, that in arranging the abutting rail sections in our improved joint, the adjacent ends thereof are permitted sufficient space to allow for expansion and contraction. 110

Manifestly, the construction shown is capable of considerable modification and

such modification as is within the scope of our claims, we consider within the spirit of our invention.

We claim:

5. 1. In a rail joint, a base plate having a plurality of spaced apart guide elements thereon for receiving the rail bases therebetween, and angle plates hingedly secured to said base.
10. 2. In a rail joint, a base plate having a plurality of oppositely disposed pairs of spaced guide elements formed thereon for receiving the adjacent portions of the rail bases therebetween, and angle plates 15 hingedly secured to said guide elements.
3. In a rail joint, a base plate having a plurality of oppositely disposed pairs of apertured lugs formed integral with one face thereof, angle plates having laterally 20 extending apertured lugs formed thereon and engageable with the apertured lugs of

the base plate to permit hinging of the same, and means engageable with the angle plates and the web portions of the adjacent rail sections for securing the same in position.

4. In a rail joint, a base plate having the opposite extremities thereof downturned, a plurality of apertured lugs formed upon one side of said base plate for receiving the 30 abutting rail sections therebetween, angle plates having laterally extending apertured lugs formed adjacent the extremities thereof engageable with said first apertured lugs to permit hinged connection therebetween, 25 and means engageable with the angle plates and the web portions of the abutting rail sections for securing the same in position.

In testimony whereof, we affix our signatures hereto.

WILLIAM C. BROWNING.
THOMAS M. LOWE.
